(57) **CLAIM**

I claim the ornamental design for a toy animal figure, as shown and described.

DESCRIPTION

FIG. 1 is a front elevational view of the toy animal figure, showing my new design;

FIG. 2 is a rear elevational view thereof;

FIG. 3 is a left side elevational view thereof. The right side elevation view is a mirror image of FIG. 3 and thus is not further illustrated; and,

FIG. 4 is a rear elevational view showing the figure upright.
